COUNTY, NORTH CAROLINA.

GAS-ENGINE ATTACHMENT.

1,133,872.

Specification of Letters Patent. Patented Mar. 30, 1915.

Application filed October 21, 1914. Serial No. 867,921.

To all whom it may concern:

Be it known that I, JOHN M. MANESS, citizen of the United States, residing at Ellerbe, in the county of Richmond and 5 State of North Carolina, have invented a certain new and useful Gas-Engine Attachment, of which the following is a specification.

This invention relates to internal combustion engines and has special reference to means for automatically controlling the supply of hydro-carbon to such engines. It is a well-known fact that after the needle-valve of the carburetor, common in engines used in automobiles and the like, is adjusted to the position usual in starting the same supply of hydrocarbon is maintained so long as the engine is running.

The principal object of the present invention is to provide an improved and efficient means for automatically decreasing the supply of hydrocarbon after the engine is started and for automatically adjusting the needle-valve when the engine is stopped 25 for restarting.

The second object of the invention is to accomplish this purpose by mechanism thermostatically controlled by the heat of the exhaust through such an engine.

With the above and other objects in view, the invention consists in general of certain novel details of construction and combinations of parts hereinafter fully described, illustrated in the accompanying drawings 35 and specifically claimed.

In the accompanying drawings, like characters of reference indicate like parts in the several views, and:—

Figure 1 is a perspective view of an automobile engine showing the device attached thereto. Fig. 2 is an enlarged detail view in perspective of the device removed from the engine.

There has been herein shown one form 45 of the device especially adapted to the peculiar engine illustrated but it will be obvious that different forms may be used with different types of engines without departing from the general principle involved.

The numeral 10 indicates the body of the engine and at 11 is shown the exhaust pipe, which usually runs along the top of the engine adjacent one side. The engine is fur-

thermore provided with the usual carburetor 12 controlled by the needle-valve, the stem 55 whereof is shown at 13.

Rigidly secured to one of the bolts 14 of the engine is an arm 15 which extends outward over the exhaust pipe. To this arm is rigidly secured one end of an expansion 60 member 16 which is preferably in the form of a tube of metal readily expansible under the influence of heat, brass pipe being preferred. This tube extends along the exhaust pipe and is preferably in contact therewith. 65 Fixed to the second bolt 14, adjacent the other end of the exhaust pipe is a bracket 17, whereto is pivoted one end of a lever 18, the lever being pivoted adjacent the bracket to the expansion member as at 19. At 20 is 70 an arm provided with a clamp 21 which surrounds and is clamped to the stem 13, and this arm is provided with a series of openings 22 through one end of which passes a pivot pin 23 to which is connected a link 75 24, the other end of the link being pivoted to one of a series of openings 25 in lever 18.

In operation the needle valve is adjusted while the engine is cold to the maximum opening required to start the engine. The 80 clamp 21 is then locked to the stem 13. When the engine is started the exhaust pipe 11 becomes heated thereby causing the expansion of the member 16. Now, since one end of this member is fixed relative to the 85 exhaust pipe the other end must move relative thereto. This causes the movement of the lever 18 and consequently acts to move the valve stem 13 in a direction which tends to close the needle-valve and thereby to cut 90 off the excess hydrocarbon, it being obvious that less hydrocarbon is necessary during the operation of the engine than is necessary to start same. When the engine is stopped the contraction of the member 16 95 acts upon the needle-valve and restores the same to starting position. Thus an economy of gasoline consumption is effected. There has thus been provided a simple and efficient device of the kind described and 100 for the purpose specified.

What is claimed as new is:—

1. The combination with a gas engine provided with an exhaust pipe and a valve for controlling the supply of hydrocarbon to 105 the engine; of an expansion member ex-

tending along and in proximity to the exhaust pipe and having one end fixed in relation to the pipe and the other end movable relative thereto, means for imparting opening and closing movement to the valve, and an operative connection between the last named end of the member and said means.

2. The combination with a gas engine provided with an exhaust pipe and with a valve for controlling the supply of hydrocarbon to the engine, said valve having a stem; of an expansion member extending along and in proximity to the exhaust pipe and having one end fixed in relation thereto, a lever pivoted to the remaining end of said member and having a fixed fulcrum, an arm car-

ried by said stem, means for locking the arm in adjusted position on the stem, and a link connecting said lever and arm. 20

3. The combination with a gas engine provided with an exhaust and a carbureter needle-valve; of an expansion member adjacent and close to and above said exhaust, means for opening and closing the valve, 25 and an operative connection between the member and the means.

In testimony whereof, I affix my signature, in the presence of two witnesses.

JOHN MOSES MANESS.
